UNITED STATES PATENT OFFICE.

BENJAMIN HOLT, OF STOCKTON, CALIFORNIA.

GRAIN-CLEANER.

SPECIFICATION forming part of Letters Patent No. 416,916, dated December 10, 1889.

Application filed August 21, 1889. Serial No. 321,514. (No model.)

To all whom it may concern:

Be it known that I, BENJAMIN HOLT, of Stockton, San Joaquin county, State of California, have invented an Improvement in 5 Grain-Cleaners; and I hereby declare the following to be a full, clear, and exact description of the same.

My invention relates to an improved grain-cleaner which is especially applicable for use 10 upon thrashing-machines, but may also be used for separate and independent cleaners when desired.

It consists, essentially, of a device for producing a shaking motion of the shoes which 15 carry the screens and a means for regulating and adjusting the shake.

Referring to the accompanying drawings for a more complete explanation of my invention, Figure 1 is an exterior side elevation of 20 the cleaner. Fig. 2 is a plan or top view of the adjustable pin-plate and the plate upon the top of the vertical shaft to which the pin-plate is attached. Fig. 3 is a longitudinal sectional view of the plates G and J, showing the crank-pin 25 and slots and bolts.

A is the exterior frame of the cleaner, which in the present case is shown as adapted to be carried upon a thrashing-machine, a portion of which is illustrated in Fig. 1, the grain to 30 be cleaned being delivered into the hopper of the cleaner from the elevator B in the usual manner.

C C are the shoes carrying the cleaning-screens. These shoes are suspended in any 35 usual or suitable manner by hangers or supports within the case, and not here shown, so as to be capable of a side shaking motion. This motion is produced by the rotation of the vertical shaft D, which is driven by belts 40 E, passing around the pulley upon said shaft, said belt receiving its power from some other portion of the machine. In the present case I have shown this belt as driven from a pulley F upon the fan-shaft. The vertical shaft

45 D has oval or elongated plates G fixed upon its upper and lower ends, as shown. I have found that this shaft may be conveniently made by casting it with these plates upon the ends. The shaft turns in the journal-boxes 50 H upon the frame of the machine. The plates G have holes or perforations made in them near each end, as shown plainly in Fig. 2.

J J are similarly-shaped plates, one being adapted to the upper and the other to the lower end of the shaft D. These plates J have 55 slots K made in their ends, the outer end of the slots being open, as shown in Fig. 2. The crank-pin L is cast with the plate J and a little to one side of the center of the plate.

M M are boxes fixed upon the sides of the 60 shoes C C and adapted to be connected with the ends of the pin L.

The plates J are fixed upon the plates G by means of bolts P with suitable holding-nuts, and it will be manifest that by reason of the 65 slots K the plates J may be moved so as to bring the crank-pins L nearer to or farther from the central shaft D, the nuts being loosened for the purpose of moving the plates, and afterward tightened, so as to clamp the 70 plates G and J firmly together. The rotation of the shaft then acts upon the crank-pins and gives the opposite side shaking movement to the upper and lower shoes C C, this shake being regulated to any degree of exactness by 75 simply moving the adjusting-plates J upon the plates G. This adjustment is easily and accurately made at any time and takes but an instant.

Having thus described my invention, what I 80 claim as new, and desire to secure by Letters Patent, is—

An improved grain-cleaner comprising a main frame, independent shaking-shoes therein, a vertical shaft having horizontal plates G, 85 formed integral with its upper and lower ends, with holes formed in said plates near the outer ends, supplemental horizontally-arranged plates J, bolted to said plates G and having integral vertical crank-pins and slotted outer 90 ends, bolts and nuts for securing the plates together, whereby they may be adjusted, and independent journal-boxes M, one of which is secured to each shaking-shoe and receives the crank-pin of the adjacent plate J, substantially as herein described. 95

In witness whereof I have hereunto set my hand.

BENJAMIN HOLT.
